SINK RETAINING MEANS

George A. Lyon, Jr., Birmingham, and Harry J. Eynon, Bloomfield Hills, Mich.; said Eynon assignor to Lyon Incorporated, Detroit, Mich., a corporation of Delaware

Filed May 12, 1959, Ser. No. 812,606

5 Claims. (Cl. 4—187)

The present invention relates generally to a sink structure and more particularly to a new and improved technique for fastening a sink to a supporting structure such as a counter.

It is well known that there is a great deal of competition between sink manufacturers to provide an improved sink construction of a type which will afford the manufacturer a competitive advantage over his competitors. Recently considerable emphasis has been placed upon providing means on the sink so that the sink may be more readily assembled with a counter structure. Formerly the installation of a sink required considerable skill since former technique were both tedious and extremely difficult to accomplish. The instant means for securing the sink in assembly with the counter structure is an improvement over previously developed similar types of retaining means, the instant retaining means being adapted to be manufactured at reduced cost in comparison with the previously developed similar types of retaining means.

According to the present invention, strip structures may be suitably preassembled by sink manufacturer on the underside of the sink so that when the sink leaves the factory it is ready for assembly with a counter structure in a home merely by assembling a fastener structure with the strip structure. To this end, the installer only need lower the sink through the opening defined by the counter structure, assemble the fastener structure with the strip structure, and then rotate the screws or bolts each comprising an element of the fastener structure to tightly clamp the sink in assembly with the counter structure.

More particularly, the present invention concerns a new and highly improved fastener structure for clamping the outer margin of the sink to the counter. Each of the fastener structures is merely comprised of two elements including a swingable arm, and a stove bolt. The swingable arm on each of the fastener structures may be turned into underlying position with respect to the sink structure by means of utilizing an arm guide which is removably attached to the strip structure disposed at the underside of the marginal flange structure of the sink, and which arm guide may be used in conjunction with the assembly of each of the fastener structures, thereby eliminating the requirement that an arm guide be provided for each of the fastener structures, as was the former practice.

Accordingly, an important object of the present invention is to provide a new and improved sink retaining means enabling speedy installation of a sink with a counter structure with a minimum of effort and expense.

Still another important object of the present invention relates to a sink retaining means which may be readily manufactured with a minimum of material, a minimum of parts, and which may be assembled with the sink with a minimum amount of labor.

A further object of the present invention relates to a new and improved sink retaining means for maintaining a sink structure in clamped assembly with a counter structure in a new and improved manner.

An important feature of the present invention relates to a sink retaining means having a swingable arm which is swingable into and out of underlying relation with respect to a counter by means of an arm guide and a bolt,

2

which swingable arm may be moved vertically to clamp the sink in assembly with the counter by the rotation of the bolt, and with the arm guide being in removable assembly with the sink retaining means so that it may be used for swinging other swingable arms into and out of underlying clamping engagement with a counter.

Still another important feature of the present invention relates to a novel strip structure which is adapted to be used in conjunction with a fastener structure to enable the sink to be clamped in assembly with a counter structure with a minimum expense.

Other objects and features of the present invention will more fully become apparent in view of the following detailed description taken in conjunction with the accompanying drawings illustrating therein a single embodiment, and in which:

FIGURE 1 is a fragmentary plan view of a sink structure with strip and fastener structure being indicated in dotted lines;

FIGURE 2 is an enlarged fragmentary view showing the strip structure in assembly with the outer margin of the sink;

FIGURE 3 is an enlarged fragmentary cross-sectional view showing a sink in preliminary engagement with a counter structure and with the illustrated sink section being taken substantially on the line III—III, as appearing in FIGURE 2;

FIGURE 4 is an enlarged fragmentary cross-sectional view taken substantially on the line IV—IV, as appearing in FIGURE 2, with the bolt and swingable arm assembly appearing in full and dotted lines illustrating the manner in which it may be assembled with the strip structure;

FIGURE 5 is an enlarged fragmentary edge elevation of the underside area of the sink but showing a portion of the marginal sink flange in section;

FIGURE 6 is an enlarged fragmentary cross-sectional view similar to FIGURE 4 only illustrating the arm guide in assembly with the strip structure;

FIGURE 7 is an enlarged fragmentary cross-sectional view similar to FIGURE 3 only showing the fastener structure partially in elevation and partially in section, and with the swingable arm being in retaining engagement with the counter;

FIGURE 8 is an enlarged fragmentary cross-sectional view similar to FIGURE 6 only showing the manner in which the arm guide may be disengaged from the strip structure;

FIGURE 9 is an enlarged fragmentary cross-sectional view taken substantially on the line IX—IX, as appearing in FIGURE 1; and

FIGURE 10 is an enlarged isometric view of the arm guide.

As shown on the drawings:

The reference numeral 8 in FIGURE 1 indicates generally a sink structure which sink structure includes a counter 9 and a sink 10. The sink 10 is illustrated as a double-bowl type sink including bowls 11 and 12 which bowls are separated by a partition rib 13. The bowls 11 and 12 are provided with discharge outlets 11a and 12a.

The counter or supporting structure may be of any suitable type and as shown is of a laminated construction having a wood layer 9a and a heat-resistant synthetic plastic layer 9b. In accordance with present day practices the counter 9 is provided with a central opening 9c through which the sink 10 is adapted to be telescoped.

When the bowl of the sink 10 is telescoped into the opening 9c the sink 10 rests upon the counter 9 by means of its marginal flange structure 14. The marginal flange structure 14 includes an annular angular flange portion 14a, a terminal curved or arched flange portion 14b, and a counter-engaging edge 14c.

According to the present invention, the sink 10 is provided with retaining means indicated generally at 15. The retaining means comprises strip structure 16 and fastener structure comprising a series of fasteners indicated generally at 17.

The fasteners 17 each include a swingable arm 18, a detachable or removable guide 19 (the guide being reusable with each of the fasteners) and a threaded bolt 20, the threads being indicated at 20a. Suffice it to say at this time that the swingable arm is mountable on the bolt and is guided in its upward movement by the arm guide 19.

The strip structure 16 comprises a metal strip or strips which are annularly arranged on the underside of the margin 14 of the sink. As is apparent in FIGURE 2, the strip structure 16 is embossed along its length providing embossed portions or offset portions 16a and 16b. The offset portions or peripherally spaced areas 16a are separated from one another by spacer portions 16c which spacer portions 16c are suitably secured to the underside of the curved or arched flange portion 14b such as by means of spot welds indicated generally at 16d. The offset portion 16b extends substantially the full length of the strip structure and is suitably secured along its length to the underside of the annular angular flange portion 14a such as by means of spot welds 16b.

Each of the offset portions 16a are provided with means which is adapted to cooperate with the bolt 20 and the arm guide 19 to assist in the assembly of these elements with the strip structure 16. To this end, the offset portions or peripherally spaced areas 16a are each provided with a key-shaped edge 16e which defines a slot through which the head of the bolt may be inserted and secured in assembly with the offset portion 16a. In addition, the offset portion 16a is provided with shoulders 16f—16f which are disposed on opposite sides of the key-shaped edge 16e and which shoulders are adapted to cooperate with the arm guide 19 in securing the arm guide in assembly with the offset portion 16a.

The swingable arm 18 has a central opening and the threaded shank of the bolt is adapted to be threadingly engaged with the opening provided on the swingable arm so that the swingable arm may move vertically relative to the shank of the bolt depending on which direction the bolt and the swingable arm are moved with respect to one another.

In order to assemble the sink 10 on the counter structure 9, the swingable arm and bolt assembly may be assembled with the strip structure 16 either before or after the sink 10 is mounted on the counter 9. The swingable arm 18 and the bolt 20 may be assembled with the strip structure by cocking the bolt 20 at an angle relative to the key-shaped strip edge 16e so that a bolt head 20b may be guided through the slot defined by the key-shaped edge. A strip edge or seat 16g is disposed above and at right angles to the key-shaped edge 16e providing an area on which the bolt head 20b may rest. The method of assembly of the bolt with the strip structure 16 is shown in FIGURE 4.

After the bolt and the swingable arm have been assembled with the strip structure 16, the arm guide 19 may be assembled with the strip structure 16. In order to attain this end, means is provided between the strip structure and the arm guide to enable the arm guide 19 to be assembled with the strip structure 16. The arm guide 19 is generally of a tubular construction and has resiliently deflectable arm guide extensions 19a which may be resiliently spread radially apart in order that arm guide seats 19b may be retainingly engaged with the strip shoulders 16f in snap-on, pull-off assembly with the strip structure 16.

To assemble the arm guide 19 with the strip structure 16, the arm guide 19 may be coaxially aligned with the bolt 20 and moved vertically relative to the bolt until the extensions 19a engage against cam strip surfaces 16h

16h (FIGURE 8). As the arm guide 19 is forceably urged against the cam strip surface 16h the tabs or extensions 19a on the arm guide are resiliently deflected along the cam surfaces so that the extensions 19a are extended through the slots and so the arm guide seats 19b, 19b are engaged with the strip shoulders 16f, 16f to thereby mount the arm guide in assembly with the strip structure.

The arm guide 19 is provided with a pair of confronting helical arm guide edges 19c, 19c which provide means for turning the swingable arm guide 18 into and out of underlying relation with respect to the counter 9 and which cooperate with the bolt 20 in moving the swingable arm guide 18 vertically relative to the bolt 20 so that the swingable arm 18 may be brought into biting engagement with the underside of the counter 9 as is shown in FIGURE 7.

In order to enable the bolt to be turned from underneath the sink structure, a slot 20c is provided on the bottom end of the bolt shank which slot is of a size capable of readily receiving a tip end of a screwdriver.

In order for the swingable arm 18 to bite into the underside of the counter 9, the swingable arm is provided within a main body portion 18a, an angular portion 18b, and a biting edge 18c disposed at the tip end of the angular portion 18b (FIGURE 7).

In summary, the swingable arm 18 and the bolt 20 are preferably initially assembled together. The assembled swingable arm and bolt may be assembled with the strip structure in the manner previously described either before or after the bowl of the sink 10 has been telescoped into the counter opening 9c in a manner whereby the sink 10 is carried on the counter 9 as a consequence of the outer marginal edge 14c of the sink 10 being in abutting engagement with the upper surface of the counter layer 9b. By the use of the arm guide 19, the swingable arms 18 may be turned into underlying relation with respect to the counter structure. The helical edges 19c, 19c on the arm guide 19 cooperate with the bolt 20 as the bolt is turned in such a manner that the swingable arm is rotated circumferentially relative to the shank of the bolt and is moved vertically relative to the underside of the counter structure into and out of biting engagement therewith. When the swingable arm is in biting engagement with the under side of the counter 9, the outer marginal counter edge 14c operates in such a manner as to prevent moisture from seeping between the counter top and the marginal sink edge 14c.

After the swingable arm has been snugly engaged against the bottom side of the counter, the arm guide 19 may be suitably grasped and pulled away from the strip structure so that the arm guide may be used again to aid in the swinging movement of other swingable arms 18. The cost of the fastener structure 17 may be reduced since only one arm guide 19 is needed to assist in the engagement of all of the swingable arms 18 with the underside of the counter. Similarly, if it is desired that the sink be disengaged from the counter 9, only one arm guide 19 is required to complete the operation. In other words, the arm guide 19 may be reassembled with the strip structure so that when the bolt 20 is turned, the swingable arm may be allowed to drop away from the underside of the counter structure and may be allowed to pivot out of underlying relation with respect to the underside of the counter.

It will be understood that modifications and variations may be effected without departing from the scope of the novel concepts of the present invention.

We claim as our invention:

1. Means for securing a sink to a counter including strip structure and a series of fastener structures removably secured to said strip structure at spaced intervals, said fastener structure including a bolt extending from one side of said strip structure and a swingable arm threadably mounted on said bolt with a biting edge at an outer end

of the arm, the improvement comprising a single guide structure having means for detachably mounting with the strip structure coaxially with said bolt and providing a guide slot through which said arm passes, said guide slot having a curvature so that the arm in moving toward the strip structure rotates relative to the strip structure.

2. The means for securing a sink to a counter of claim 1 further characterized by the strip structure having a series of peripherally spaced areas with which the means on the arm guide is adapted to be selectively secured in 10 removable assembly.

3. The means for securing a sink to a counter of claim 2 further characterized by the peripherally spaced areas on the strip structure each including a pair of strip retaining shoulders, and the guide structure having a pair 15 of complementary resiliently deflectable extensions removably engageable under tension with the strip retaining shoulders.

4. The means for securing a sink to a counter of claim 2 further characterized by the peripherally spaced areas 20 each having a key shaped edge in which a head of said bolt may be inserted through enabling the bolt to be suspended from the strip structure to assist in the clamping of the sink to the counter.

5. Means for securing a sink to a counter including strip 25

structure and a series of fastener structures removably secured to said strip structure at spaced intervals, said fastener structure including a bolt extending from one side of said strip structure and a swingable arm threadably mounted on said bolt with a biting edge at an outer end of the arm, the improvement comprising a single guide structure having means for detachably mounting with the strip structure coaxially with said bolt and providing a guide slot through which said arm passes, said guide slot having a curvature so that the arm in moving toward the strip structure rotates relative to the strip structure, the biting edge being disposed outwardly of the guide structure.
